US0D1050086S

(12) **United States Design Patent** (10) **Patent No.:** **US D1,050,086 S**
(45) **Date of Patent:** **** Nov. 5, 2024**

(54) **PAIR OF SOUND BAR SUPPORT BRACKETS**

(71) Applicant: **OHOPE ERGONOMIC TECHNOLOGY CO., LTD**, Shenzhen (CN)

(72) Inventors: **Hairu Chen**, Guangdong (CN); **Li Xiao**, Guangdong (CN)

(73) Assignee: **Ohope Ergonomic Technology Co., Ltd**, Shenzhen (CN)

(**) Term: **15 Years**

(21) Appl. No.: **35/516,782**

(22) Filed: **Mar. 10, 2023**

(80) **Hague Agreement Data**

Int. Filing Date: **Mar. 10, 2023**

Int. Reg. No.: **DM/227742**

Int. Reg. Date: **Mar. 10, 2023**

Int. Reg. Pub. Date: **Mar. 31, 2023**

(30) **Foreign Application Priority Data**

Sep. 29, 2022 (CN) 202230648388.1

(51) **LOC (14) Cl.** **14-01**

(52) **U.S. Cl.**

USPC **D14/224**
